US0D1068046S

(12) **United States Design Patent** (10) Patent No.: **US D1,068,046 S**
(45) Date of Patent: ** Mar. 25, 2025

(54) **NECK FAN**

(71) Applicant: **Liying Deng**, Hunan (CN)

(72) Inventor: **Liying Deng**, Hunan (CN)

(**) Term: **15 Years**

(21) Appl. No.: **29/907,330**

(22) Filed: **Jan. 5, 2024**

(51) LOC (15) Cl. **23-04**

(52) U.S. Cl.

USPC **D23/380**

(58) **Field of Classification Search**

USPC D23/332, 333, 351, 370, 380

CPC F04D 29/4226; F04D 29/424

See application file for complete search history.

(57) **CLAIM**

The ornamental design for a neck fan, as shown and described.

DESCRIPTION

FIG. 1 is a front perspective view of a neck fan showing my new design.

FIG. 2 is a rear perspective view thereof.

FIG. 3 is a front view thereof.

FIG. 4 is a rear view thereof.

FIG. 5 is a left side view thereof.

FIG. 6 is a right side view thereof.

FIG. 7 is a top view thereof; and,

FIG. 8 is a bottom view thereof.

The broken lines illustrate portions of the neck fan that form no part of the claimed design.

1 Claim, 8 Drawing Sheets
